A. B. Reavis
ATTORNEY

UNITED STATES PATENT OFFICE.

DAVID W. R. MORGAN, OF SWARTHMORE, PENNSYLVANIA, ASSIGNOR TO WESTINGHOUSE ELECTRIC & MANUFACTURING COMPANY, A CORPORATION OF PENNSYLVANIA.

SURFACE CONDENSER.

Application filed February 24, 1927. Serial No. 170,607.

My invention relates to surface condensers of the type in which means are provided for passing circulating media through only a certain group, or groups of tubes. As well as through all of the tubes of the nest.

These condensers may be of the radial flow type, and also may be provided with a centrally disposed, divided, air and non-condensable gas offtake, all as fully set forth 10 and claimed in the application of John H. Smith, Serial No. 145,198, filed October 30, 1926; and, accordingly, I make no claim to the apparatus disclosed and claimed in said application.

An object of my invention is to provide a directing means for a device of the type described, which shall be of simple and rugged construction, and which may be so disposed as not to interfere with the normal operation 20 of the condenser and yet be effective for directing gaseous media to active tubes when a portion of the nest is rendered ineffective.

Another object of my invention is to provide a directing means, for a device of the 25 type described, which shall be effective to prevent the by-passing of gaseous media, from an inactive portion of the nest, directly to the portions of the air and non-condensable gas offtake.

Various other and further objects of my 30 invention will appear as the description proceeds.

Apparatus embodying the features of my invention is shown in the accompanying 35 drawings, in which:

Fig. 1 is an elevational view, partly in section, of a surface condenser with its tubes removed;

Fig. 2 is a section on the plane II-II of 40 Fig. 1, showing the general arrangement of the tube nest; and,

Fig. 3 is an end view of the condenser shown in Fig. 1 and partly in section to show the interior construction of the water box.

According to my invention, a directing 45 means, such as a baffle, is arranged between portions of the nest which are adapted to be cut out of the circulating system. This baffle extends a sufficient distance from the air removal means to assure that motive fluid will not be by-passed directly from an inactive portion of the nest to the air removal means. In this way, it is assured 50 that all gases entering the condenser will

have a proper path of vapor travel, and will 55 come in contact with an adequate number of cooling tubes. This baffle preferably terminates a sufficient distance inside the periphery of the tube nest to permit gases, which may enter an inactive portion of the nest, to be withdrawn around the ends of the baffle to the active side.

In the drawings, I show my invention embodied in a radial flow type of surface 60 condenser, indicated generally at 10, and having a shell 11, a steam inlet 12 and a hot-well 13. This condenser is equipped with water boxes 14 and 15, which are divided by suitable partition means 16. The partition means may be arranged substantially 65 on the vertical centerline of the water boxes so as to provide substantially equal compartments, as shown in Fig. 3.

Suitable inlet connections for the water 70 box 15, such as connections 17 and 18 may be provided, and outlet connections such as 19 and 21 may be provided for the water box 14. Valves 22, 23, 24 and 25, are provided in these connections so that the conditions of 75 flow, in the portions of the tube nest associated with the respective compartments of the water boxes, may be separately controllable; and, in this way, a portion of the tube nest associated with one of the compartments of the water box may be completely 80 cut out of service.

Any suitable tube supports, such as indicated at 20, may be provided for the nest of tubes 26. Extending through the core of the tube nest 26 is an air offtake 27, which 85 is in the form of a rectangular box-like structure, and extends substantially the entire length of the tube nest. Openings 28 are provided in the lateral walls of the offtake for receiving air and other non-condensable gases from the tube nest. Any 90 suitable means, such as the tray 30, may be disposed above the offtake and in overhanging relation therewith, for collecting condensate from tubes above the offtake.

The offtake 27 is also preferably divided 95 by solid partition means 29 into separate compartments 31 and 32. The compartment 31 is in direct communication with the conduit 33 while the compartment 32 is in direct communication with the offtake conduit 34.

Both of these conduits lead to any suitable

air removal means (not shown). Preferably, however, I provide valves 36 and 37 for controlling the flow of fluid through these conduits to a common lead such as shown at 38, from which air and non-condensable gases may be removed by any suitable air removal means.

Extending substantially the entire length of the tube nest, and arranged between the respective portions of the nest, which are rendered separately controllable by means of valves 22, 23, 24 and 25, is a directing means, or baffle member 39, which is arranged substantially on the vertical center-line of the nest. This baffle member extends radially from the air offtake 27 toward the periphery of the nest, and is so disposed as to leave a relatively narrow passage 41 below the lower extremity of the baffle from one side of the nest to the other, and a similar passage 42, which may be somewhat larger, is left above the baffle for permitting condensable gases to pass, above the baffle, from one side of the nest to the other.

If desired, suitable bracing, or stiffening, means, such as angles 43 may be arranged longitudinally of the baffle 39 as shown in Fig. 2.

Suitable means, such as manholes, or doors 44, as shown in Fig. 3 are provided for each part of each divided water box in order that, when half of the condenser is rendered ineffective, tubes of the latter may be rendered accessible for cleaning.

In the normal operation of the condenser shown, the valves 22, 23, 24 and 25 are all open, and circulating media, such as cooling water, passes through all of the tubes, and the condenser functions in the manner well known in the art.

During a period of relatively light load, the valves controlling the flow of cooling media through one side of the nest, as, for example, valves 24, 25 may be closed, thus rendering the side of the nest controlled by these valves, in this case the right side in Fig. 3, ineffective.

Valve 37, controlling the air removal means for this side, would also be closed, so that there would be no tendency for uncondensed motive fluid to be drawn over to the inactive side and, likewise, this selective control of the air removal means insures that uncondensed motive fluid will not be withdrawn from the inactive side of the nest through the air removal means.

In this way, it is assured that gases, entering the inactive side of the nest, must pass to the active side and, since the only avenue of escape for such gases is around the ends of the vertically extending baffle, through passages 41 and 42, it will readily be seen that by-passing of uncondensed gases from the inactive side of the nest directly to the air removal ports on the active side of

the nest is effectively prevented. Furthermore, it will be apparent that uncondensed gases, in passing from the inactive to the active side of the nest, will be compelled to come in contact with the proper number of active tubes before reaching the active ports of the air removal apparatus.

While a portion of the tubes of the nest are thus cut out of the circulating system, access may be had to such tubes for cleaning, testing, or the like, through suitable openings, such as the manholes, or doors 44, provided on the water boxes, and the cleaning, or other work, may then be carried on without interference with the operation of the plant. When the cleaning has been completed the valves 24, 25, controlling the cooling media, and valve 37, controlling the air removal means, may again be opened, restoring the condenser to normal operating conditions.

It will also be noted that during the normal operation, the baffle 39 does not in any way interfere with the operation of the condenser.

While I have shown my invention in but one form, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

I claim—

1. In a condenser comprising a shell, a nest of tubes within the shell, and separate controllable means for directing cooling media through respective portions of the nest, the combination of separate controllable means for removing air and non-condensable gases from the respective portions of the nest, and directing means extending longitudinally of the nest and between said respective portions of the nest for preventing condensable gases from by-passing from one of said respective portions of the nest directly to said means for removing air and non-condensable gases from another of said respective portions of the nest.

2. In a condenser comprising a shell, a nest of tubes within the shell, and separate controllable means for directing cooling media through respective portions of the nest, the combination of separate controllable means for removing air and non-condensable gases from the respective portions of the nest, and directing means on a diameter of the nest and between said respective portions of the nest for preventing condensable gases from by-passing from one of said respective portions of the nest directly to said means for removing air and non-condensable gases from another of said respective portions of the nest.

3. In a condenser comprising a shell, a nest of tubes within the shell, and separate controllable means for directing cooling media through respective portions of the nest, the combination of separate controllable means for removing air and non-condensable gases from the respective portions of the nest and directing means on a diameter of the nest and between said respective portions of the nest for preventing condensable gases from by-passing from one of said respective portions of the nest directly to said means for removing air and non-condensable gases from another of said respective portions of the nest, said directing means being entirely within the periphery of said nest. 55
5. In a condenser comprising a shell, a nest of tubes within the shell, and separate controllable means for directing cooling media through respective portions of the nest, the combination of separate controllable means for removing air and non-condensable gases from the respective portions of the nest, and directing means extending, from said controllable means for removing air and non-condensable gases, toward the periphery of the nest for preventing condensable gases from by-passing from one of said respective portions of the nest directly to said means for removing air and non-condensable gases from another of said respective portions of the nest, said directing means being between the respective controllable portions of the nest. 60
6. In a condenser comprising a shell, a nest of substantially horizontally disposed tubes within the shell, and separate controllable means for directing cooling media through respective portions of the nest, the combination of separate controllable means for removing air and non-condensable gases from the respective portions of the nest, and a baffle between the respective portions of the nest and on the vertical centerline of the nest, said baffle being within the periphery of the nest and extending longitudinally for substantially the entire length of the nest. 65
7. In a radial flow condenser having a tube nest, the combination of an offtake means within the nest and having lateral admission openings, a partition for dividing the offtake longitudinally into passageway portions arranged side-by-side, and baffle means extending above and below the offtake means and terminating in proximity to the outermost tubes of the nest. 70
8. In a radial flow condenser having a tube nest, the combination of means providing a plurality of air offtake passages having lateral admission openings, said passages being arranged side-by-side, and baffle means extending above and below the offtake means and terminating in proximity to the outermost tubes of the nest. 80
9. In a radial flow condenser having a tube nest, the combination of means providing a plurality of adjacent air offtake passages having lateral openings, and baffle means extending substantially radially substantially from the limits of adjacent passages and terminating in proximity to the outermost tubes of the nest. 85
10. In a radial flow condenser having a tube nest, the combination of means providing a plurality of adjacent air offtake passages having lateral openings, and substantially radially extending baffle means terminating between the ports of adjacent passages. 90
- In testimony whereof, I have hereunto subscribed my name this 21st day of February, 1927. 100
- DAVID W. R. MORGAN.
